UNITED STATES PATENT OFFICE

ALBERT REPPMAN, OF LONDON, ENGLAND

ADJUSTABLE ROOF FOR FURNACES

Application filed May 7, 1928, Serial No. 275,892, and in Great Britain March 5, 1928.

This invention relates to roofs for boiler and other furnaces of the kind in which the roof is formed of suspended elements adjustable for wear and to meet varying combustion requirements, the object of the present invention being to provide an improved construction and arrangement of suspended furnace roof which permits of easy adjustment without rebuilding and whilst the furnace is in operation and ensures that in all adjustments of contour an unbroken internal surface is maintained in the furnace roof.

According to the invention a roof for furnaces and the like having means for varying the internal contour and height is provided wherein the roof is constructed in a plurality of sections so interconnected that adjustment in the position of one section automatically causes the adjacent section or sections to be correspondingly adjusted for the purpose of ensuring the preservation of an unbroken surface in the furnace roof irrespective of changes in contour. According to the preferred form of carrying the invention into effect the roof sections are provided with a number of upwardly extending webs or flanges which are linked to the supporting members and which enable the adjacent sections to be linked or pivotally connected together.

Reference will now be made to the accompanying drawings which illustrate by way of example constructions according to the invention and in which:

Figure 1 is a longitudinal section through the roof of a water tube boiler furnace,

Figure 2 is a partial cross sectional elevation through the furnace shown in Figure 1,

Figure 3 is a longitudinal sectional elevation of an alternative form of construction, and

Figure 4 is a partial cross sectional elevation of the furnace roof shown in Figure 3.

Referring first to Figures 1 and 2, the adjustable furnace roof illustrated comprises two adjustable sections *a* and *b*, the former being disposed adjacent the entrance to the furnace, whilst the latter is disposed in a succeeding position and terminates in an upwardly curved inner end *c* which in its

uppermost position as shown abuts against a bridge *d* over which the gases of combustion pass to the boiler tubes *e*. Each of the roof sections comprises a series of refractory blocks which are formed on their upper surfaces or edges with dove-tail shaped slots *f* (see Figure 2) which are engaged by metal hanger bars *g* also of dove-tail cross section, a number of which extend longitudinally of each of the furnace sections *a* and *b*. The bars *g* are formed integral with or have secured thereto a number of upwardly extending webs, flanges or lugs *h*, *i*, *j*, and *k*, which serve in the first place for the suspension of the roof sections from a number of transverse beams *l*, *m* and *n* carried adjustably on steel bearers or cleats *o* of the furnace supported by the fabric steelwork. These beams are preferably supported by screw jack or adjustable devices *p* as shown in Figure 2 which enable them to be adjusted in height from the exterior of the furnace without the necessity of dismantling or rebuilding. Two methods of suspension are shown in Figure 1. The forward end of the roof section *a* is suspended from beam *l* formed by assembling two channel-shaped elements with a space between them, through which space passes a series of bolts *q*, the lower ends of which are provided with enlargements *r* which are slotted and secured to the flanges *h* of the hanger bars *g* by nuts and bolts *s*. The upper ends of the bolts *q* pass through flanged plates *t*, above which are secured lock nuts *u* which permit a certain degree of adjustment in the assembly of the flanges *h* to the beam. The flanges *i* of the hanger bars *g* are connected to the flanges *j* of the hanger bars *g* on the adjacent roof section *b* by links *v*, the disposition of which is such as to permit movement of the section *b* towards or away from the section *a* without altering the pivotal height of the latter, although any alteration in the vertical height of the forward end of section *b* will be automatically transferred through the links *v* to the section *a* and thus preserve an unbroken internal roof surface irrespective of changes in contour such as are indicated by the broken lines in Figure 1 which may be effected by lifting or lowering

the transverse supporting beam *n*. The mid portion of the roof section *b* is connected by links *w* to members *x* which bridge the space between the internal lower flanges of the pair of beams *m* whilst each flange *k* of the hanger bars *g* at the rear end of the roof section *b* is connected to the beam *n* by means similar to those already described in connection with the beam *l*. Thus, any adjustment in the vertical height of the beam *n* causes the roof section to pivot around its point of suspension from the beam *m* to alter the angle at a point remote from the pivot axis.

In the modified form of construction illustrated in Figures 3 and 4 the same letters of reference are used to denote parts corresponding to parts in Figures 1 and 2. In this construction, however, suspension of the roof sections is entirely by means of bolts and the adjustment in height of the supporting beam *n* is effected by a worm and worm wheel arrangement *y* which rotates a screw-threaded spindle carrying a sleeve *z* by which vertical movement is imparted to the supporting beam. In Figure 3 two alternative contours which may be obtained in the furnace roof by adjusting the positions of the supporting beam are indicated in broken lines. In building the furnace with a roof formed according to the invention spaces 2 are provided in the side walls to receive a filling or plugging if the roof be raised. If the roof be lowered the filling-in material is removed, but the roof should not be dropped direct on the offset bricks in the wall since space must be provided for expansion. Usually a making-up brick 3 is provided, as shown in dotted lines Figure 2.

I claim:—

40. 1. A roof for furnaces composed of serially and link-connected arch sections, and adjustable supports for the sections disposed to permit said sections to be supported at various angles to each other and to maintain a continuity of the inner faces of the sections.
45. 2. The combination with a furnace having transverse supports, of a roof therefor comprising a plurality of sections, each section comprising a plurality of refractory blocks and metallic hanger bars, means including links connecting hanger bars of adjacent sections together, and adjustable supporting means for the sections connected to the transverse supports and the hanger bars.
50. 3. The combination with a furnace having transverse supports, of a roof therefor comprising a plurality of sections, each section including a plurality of hanger bars and refractory blocks supported on said bars, said bars being provided with apertured lugs upon their sides opposite to the blocks, link means connecting the lugs of the adjacent bars, rods pivotally connected to the remain-

ing lugs of said hanger bars, and vertically adjustable means connecting the rods to the transverse supports to adjustably suspend the sections from said supports.

4. A roof for furnaces or the like, comprising a plurality of supporting members, a pair of sections arranged end to end, each of said sections comprising a plurality of hanger bars below said supports transversely of the latter and a plurality of parallel rows of refractory blocks suspended from said hanger bars, links connecting the hanger bars of said sections adjacent the adjoining ends of the latter, vertically adjustable means supporting the hanger bars of each of said sections adjacent their other ends from one of said supports, and means supporting the hanger bars of one of said sections between their ends for rocking movement on a horizontal axis.

5. A roof for furnaces or the like according to claim 4 wherein the means which supports the hanger bars of one of the sections between the ends of the latter comprises links depending from one of the supports and vertically adjustable toward and away from the latter.

In witness whereof I affix my signature.

ALBERT REPPMAN.
